UNITED STATES PATENT OFFICE.

WALTER L. SIEWERS, OF WINSTON-SALEM, NORTH CAROLINA, ASSIGNOR TO THE INDEA MILLS, OF WINSTON-SALEM, NORTH CAROLINA, A COPARTNERSHIP
CONSISTING OF W. L. SIEWERS AND F. H. FRIES.

DESIGN FOR AN UNDERGARMENT OR ARTICLE OF SIMILAR NATURE.

58,405.

Specification for Design.

Patented July 12, 1921.

Application filed March 15, 1920. Serial No. 366,133. Term of patent 7 years.

To all whom it may concern:

Be it known that I, WALTER L. SIEWERS, a citizen of the United States, residing at Winston-Salem, in the county of Forsyth and State of North Carolina, have invented a new, original, and ornamental Design for an Undergarment or Article of Similar Nature, as shown in the accompanying drawing and described in the following specification.

The figure is a perspective view of an undergarment—namely, a petticoat—showing my new design.

I claim:

The ornamental design for an undergarment or article of similar nature as shown.

WALTER L. SIEWERS.

Witnesses:

ANNA COX,
J. LEO KEIGER.
